Sept. 30, 1930.

K. D'ARLET

1,777,027

WRIST VANITY CASE

Filed Dec. 21, 1927

INVENTOR
Kama d'Arlet,

BY W. H. Barker
ATTORNEY

UNITED STATES PATENT OFFICE

KAMA D'ARLET, OF NEW YORK, N. Y.

WRIST VANITY CASE

Application filed December 21, 1927. Serial No. 241,478.

The invention herein described relates to a novelty device commonly known as a compact or vanity case which in its adaptation illustrated herein is designed to be worn to simulate a wrist watch or may be worn as a garter or anklet bracelet. 5

It consists essentially of a container of rather unique form which will hold the usual accessories of "powder puff", "rouge" and 10 "lip stick", which have come into common use as an accessory to the well dressed woman.

In addition to this, a mirror is provided so that the "makeup" may be properly applied.

15 Of course, vanity cases of various sorts have come into common use, but the intention of the present invention is to provide a very simple form of device which is compact, worn upon the wrist and readily accessible 20 as to all of its component elements.

Referring to the drawings:

Figure 1 is a perspective view of the device showing the vanity case and band for securing it to the arm.

25 Figure 2 is illustrative of the device when open.

Figure 3 shows the adjusting band with the fastener closed.

Figure 4 shows the fastener open for adjustment on the wrist.

Figure 5 shows a modification in which the mirror is arranged interiorly of the casing.

The main essentials of the vanity case are 35 that there shall be a mirror, by which the "makeup" may be applied, a container with the "lip stick", "rouge" and "powder puff".

In the device herein described, all of these elements have been coalesced and reduced 40 into an artistic form through which the necessary elements are immediately available on the wrist of the wearer.

Of course, hand bags have been provided with such paraphernalia and vanity cases of 45 innumerable types have been devised which may be carried in a hand bag or suspended on a finger ring, but all such devices require removal from the hand bag or an immediate exposition of use by opening a vanity case.

50 As hereinafter defined, these objections are eliminated by providing a device having all the advantages of the ordinary vanity case, but applied to the wrist of the wearer to simulate a bracelet or wrist watch, so that the user may conveniently apply the cosmetics contained therein without undue discomfort or observation of the public. 55

In the accompanying drawings, numeral 1, denotes the vanity case and 2, the band by which it may be secured to the wrist, ankle 60 or as a garter.

The device is always ready at hand for use and does not necessitate the use of a hand bag with its attendant possibility of loss or misplacement or a search through the 65 hand bag with a possible liability of loss of articles from the bag. Furthermore, it does not become a care to the user, as does the so-called finger ring vanity case. It is usually worn upon the wrist and leaves the hands 70 free.

The vanity case consists of any artistic form which is made in two parts, a base 2', and cover 3, properly associated and hinged and with a snap closure 4, which may be released by pressure of a thumb button 5. 75

As illustrated, the case is made in the form of an oval wrist watch, the stem of the watch being the thumb button 5, which is knurled to simulate a watch stem, the pressure upon the thumb button or stem 5, immediately makes the contents of the vanity case available for use and the arrangement of the pockets or recesses for containing the rouge pact, powder pact or lip stick are so constructed in the base or cover of the casing that the device may be comparatively thin and not cumbersome or noticeable any more than a watch would be. 80

Extending over the knurled portion is a 90 loop 6, and at the opposite end of the lower portion of the casing is a loop 7.

Through these loops are passed or secured the band 2. One end of the band is passed through the loop and attached to a clasp member 8, through which the band passes. The clasp member has a movable clamp 9, by which the loop and band may be adjusted upon the wrist. 95

Any convenient form of adjusting device 100 and clamp or lock for the band may be employed and the band may be of textile or ribbon form or it may be of metal, so long as it performs its function of securing the case 5 in place.

As illustrated in Figures 1 and 2, the principal cover portion has a mirror 10, which takes the place of the ordinary crystal of a watch. Within the cover is a clasp 11, for 10 holding a "lip stick" 12. Within the bottom portion of the casing which, with the cover is somewhat curved to fit the wrist, there is a recess 13, for a compact of rouge and an intermediate recess 14, for a compact 15 of powder and puff and below a depression 15, into which the lip stick projects when the cover is closed.

This arrangement provides a very compact structure which is not unusually cumbersome. 20

In Figure 5, there is a small modified arrangement in which the cover portion 3 is embellished exteriorly in any desirable ornate design and worked into this design there is 25 a wrist portion 16, which serves as a recess for the lip stick. The lip stick in this case, is secured in a clip 17, in the lower section of the case, and this permits the insertion of a mirror 18, within the cover 3.

Of course, if desired, the exterior finish of 30 the cover may simulate a watch having minute and hour hands and indicia simulating a watch, or it may be embellished in any fanciful or artistic design.

Whether the mirror is on the exterior surface of the cover or on the interior surface thereof, the use of the device is not changed.

The user by pressing upon the stem 5, opens the cover and has immediate access to 40 the various cosmetics desired and the mirror serves as a convenient means for applying the same.

Obviously, the exact details and design features of the device, as illustrated by the 45 drawings, need not be adhered to.

The principal object being to provide a bracelet like structure having all the necessary features of a vanity case and simulating, to an extent, a wrist watch or bracelet.

What I claim as my invention and desire 50 to secure by Letters Patent is:

1. In a device of the character described, a casing conforming to the wrist of the wearer, consisting of a base portion and cover, a stem 55 holding the cover and base in locked position and movable to release the cover from the base, a mirror forming a part of the cover, means in said cover for the holding of a lip stick, a recess in the base for holding a rouge pact, powder pact and puff.

2. In a device of the character described, a casing and cover therefor, a stem holding 60 the cover and base in locked position and movable to release the cover from base, a mirror forming a part of the cover, a recess formed partially in the cover and partially in the base for receiving a lipstick, said lipstick held by a clip to one of the elements, and recesses in the base for holding a rouge pact powder pact and puff.

KAMA D'ARLET.

70

75

80

85

90

95

100

105

110

115

120

125

130